UNITED STATES PATENT OFFICE.

EDWIN B. STIMPSON, OF BROOKLYN, E. D., NEW YORK.

DESIGN FOR AN ORNAMENTAL BORDER.

SPECIFICATION forming part of Design No. 12,055, dated December 7, 1880.

Application filed September 1, 1880. Term of patent 3½ years.

To all whom it may concern:

Be it known that I, EDWIN B. STIMPSON, of Brooklyn, E. D., in the county of Kings and State of New York, have invented a new and original Design for an Ornamental Border, of which the following is a specification.

The accompanying printed illustration represents a face view of my newly-designed border.

10 This invention relates to a new and original design for a border, which may be stamped or otherwise cut in paper, thin sheet metal, or any other suitable fabric or material, and is designed to be used for the lining or trimming of paper boxes, bird-cages, frames, for trimming shelves, ornamenting ceilings, or any other purpose for which it may be adapted, as the judgment of the user may indicate. I propose, however, to employ it chiefly in the form of a stamped paper border.

15 In the printed illustration filed herewith, A represents a seven-pointed star. B is a pointed scallop border, the apex of each scallop being occupied by a small group, c, of dots or perforations.

20 D represents a series or group of dots or perforations arranged in circles, the center of each circle being perforated or dotted, as at d. e e are dots or perforations midway between the circles of each consecutive pair, and E E are elongated pointed figures, each situated in line with one of the dots e and the center of one of the stars A.

25 By preference I surround the stars A with a series of dots or perforations, perforations a being preferably employed, especially when paper is used for the border; but the bounda-

ries of the stars may be formed of continuous lines, which may be printed upon the border when preferred.

40 As shown in the accompanying illustration, the dots or perforations a are diamond-shaped or lozenge-shaped and formed with their central longitudinal lines substantially perpendicular to radii drawn from the center of the star, 45 there being one of these lozenge-shaped figures between the points of each consecutive pair of the points on the star.

45 The bounding-lines of the pointed scallops B extend downwardly or inwardly upon the 50 border far enough to partially surround the stars A.

I claim—

1. The design for a border having the stars A and the row of circles D beneath said stars, 55 substantially as shown.

2. The design for a border having the pointed scallops B, the groups of dots c at the apex of said scallop, the stars A, and the lozenge-shaped dots or perforations a, situated substantially equidistant from each other and from the center of the star, substantially as shown.

3. The design for a border having the stars A, the row of circles D below the stars, and 65 the groups of dots c arranged above the stars, substantially as shown.

In testimony whereof I affix my signature in presence of two witnesses.

EDWIN B. STIMPSON.
